UNITED STATES PATENT OFFICE.

RUDOLF KNOLL, OF ENNET-BADEN, SWITZERLAND.

DYNAMO-ELECTRIC MACHINERY.

1,255,838.

Specification of Letters Patent.

Patented Feb. 5, 1918.

Application filed March 20, 1916. Serial No. 85,496.

To all whom it may concern:

Be it known that I, RUDOLF KNOLL, a subject of the Austrian Emperor, and residing at Villa Erika, Ennet-Baden, Switzerland, have invented certain new and useful Improvements in and Relating to Dynamo-Electric Machinery, of which the following is a specification.

This invention relates to uni-polar or 10 homo-polar dynamo electric machines.

A drawback of almost all uni-polar machines is this, that only comparatively low voltages can be generated. This drawback can be remedied to a certain extent by connecting in series a plurality of armature conductors by means of non-inductive return conductors, the ends of which terminate, for instance, in the segments of two commutators, one on each side of the magnetic field.

All machines heretofore constructed or proposed so far as I know, have the fault that proper access to the brushes cannot be secured. If it is desired to utilize the machine efficiently the brushes must be distributed around the entire circumference of the commutators or of the slip rings where such are used. On the other hand, it is not possible to provide in the yoke which serves for 20 the return connection of the lines of force, a sufficiently large number of apertures through which the brushes can be attended to, because the provision of numerous holes would weaken the magnetic cross-section too much.

The object of the present invention is to provide a uni-polar machine free of these disadvantages.

The invention mainly consists in making 40 the brush rocker rotatable for the purpose of facilitating inspection of the brushes.

The invention also consists in using a rotatable brush rocker comprising a hollow iron cylinder (which may in some circumstances be composed of a plurality of single metal sheets) through which the return conductors which serve also as brush holders, are led but are insulated therefrom.

The invention further consists in a commutator for uni-polar machines in which

contact between the armature conductors and the commutator segments is effected simply by pressing the segments on the conductors.

The invention further consists in arranging the conductors in two or more layers for the purpose of attaining high voltages, the commutator segments being correspondingly sub-divided axially.

Referring to the accompanying diagrammatic drawings:

Figure 1 is a longitudinal section and Fig. 2 a cross section of one construction according to the present invention.

Fig. 3 shows how the commutator segments can be pressed on to the armature conductors.

Figs. 4 and 5 are developed views, showing two arrangements of segments and brushes.

Fig. 6 illustrates a form in which a hollow cylinder surrounding the return conductors extends up to the air gap of the machine, the return conductors which serve also as brush holders being led through the cylinder but insulated therefrom.

Figs. 7 and 8 show a part longitudinal section and a developed view respectively of a modification in which two layers of conductors are employed.

Fig. 9 is a perspective view of a detail.

In the form shown in Figs. 1 and 2, the brush rocker consists of cast iron or cast steel segments c_1 to c_{12} . They are held together by a steel cylinder d .

The segments are insulated from this cylinder as well as from one another. For larger potentials they may also be insulated from the cylinder b .

The segments may either be arranged axially (Fig. 4), or they may be inclined to the extent of the pitch of a brush (Fig. 5). The brush holders are bolted on at both sides in such a manner that two brushes connected by a segment c can be shifted relatively to each other to the extent of the pitch of a brush (Figs. 4 and 5).

Figs. 4 and 5 show the course of the current. The current is supplied at two adjacent brushes e_1 and e_3 to the machine; flows

in two branches from e_1 and e_3 through the armature conductors a_1, a_2 , as indicated by the broken lines, to the brushes e_2 and e_4 ; from the latter as shown by the thin full lines, back to the brushes e_3 and e_{23} ; from these back through the armature conductors to the other side of the machine, and so on. Finally, the current passes out at e_{14} and e_{15} . The current may also be admitted and taken in the manner indicated by the dash and dot lines (Fig. 4).

The brush rocker is mounted on ball or roller bearings k , so that it can be rotated for the purpose of adjusting the brushes. 15 In a machine as shown in Fig. 1, the brush rocker can be rotated only while the machine is at rest.

It may however be desirable to be able to inspect or adjust all the brushes also during 20 the working of the machine. This requirement can be readily satisfied by mounting at both sides of the brush rocker an insulated slip ring $m' m$ to which the beginning and the end of the winding are connected respectively. The current is taken from one slip ring and is supplied to the other slip ring.

The brush holders are movably mounted in radial guides for the purpose of enabling them to be adjusted when the commutator 25 has become worn.

The brushes do not as shown in Fig. 1 run directly on the armature conductors. The latter would become worn out too quickly, and are also not replaceable with sufficient 30 ease. For these reasons easily removable segments s_1 to s_{15} are provided, consisting of hard material; for instance, nickel steel. The contact between the conductors a_1, a_2 , etc., and the segments s_1, s_2 , etc., is made 35 in an extremely simple manner by pressing the segments on the conductors (Fig. 3).

The segments s_1, s_2 , etc., are held together by shrunk-on rings r . The segments are also held by the conically bored ends of the steel 40 cylinders f and f_1 pressed on to the conductors a_1, a_2 , etc., but insulated therefrom.

Where the segments s_1, s_2 , etc., are composed of material of small magnetic resistivity, for instance, steel, it might easily happen that a portion of the magnetic flux would be rendered useless for the generation of the current by reason of the fact that it was closed upon itself outside the conductors a_1, a_2 , etc., from the end of the drum R 45 through the sleeve f and through the segments s_1, s_2 , etc., and the sleeve f ; the respective lines of force would then not be cut by the conductors a . In order to oppose a high magnetic resistance to this dispersion of the 50 flux, the segments s_1, s_2 , etc., may be provided with recesses or openings g under the shrunk-on ring r . Or for the same purpose the insulation may be made particularly

thick between the segments s_1, s_2 , etc., and the cylinders f and f_1 ; or material of great 55 magnetic resistivity may be inserted between the segments s and the cylinders f and f_1 .

l_1, l_2 are grooves which serve for cooling the commutator and which extend under the conductors a from one end of the rotor to the other (Fig. 3). Air can be supplied to them through the pipe z .

In the machine described above, the stationary return conductors are arranged in the manner of a commutator around the 75 armature, while, however, being rotatable as a whole from the outside of the machine with relation to the fixed magnetic system, so that the brushes which are connected to these return conductors can be readily inspected 80 and adjusted. In that form the aforesaid conductors were held together by a surrounding insulated steel cylinder d mounted on rollers or balls in the magnetic housing.

According to the modification shown in 85 Fig. 6, the hollow cylinder d which surrounds the return conductors is made to extend up to the air gap of the machine, and the return conductors c which serve also as brush holders, are led in an insulated manner through openings or holes in the hollow cylinder d . This cylinder may be made of solid iron or of assembled metal sheets. The mounting may be effected, as before, by 90 means of rollers or balls.

The form of the invention illustrated in 95 Fig. 7 shows a machine for the production of high voltages. In this form the commutator segments are sub-divided in the axial direction so that a plurality of commutators are 100 located in an insulated manner on each side of the machine. The armature conductors are also sub-divided, but in the radial direction, and the several conductors are insulated from one another. In other respects 105 the construction is the same as described above.

The course of the current in the machine is shown in Fig. 8. The current is taken, for example, by the brush e_1 from the commutator; flows as indicated by the broken line through the return segments e_2 to the brush e_2 ; from the latter as indicated by the dot and dash line through an armature conductor to the brush e_3 , and from the latter again, as indicated by the dotted line, through the return segments e_4 to the brush e_4 and so on.

With this sub-division of the commutators the potential due to the self-induction which 110 occurs on the disconnecting of each armature conductor, can be suppressed by staggering the brushes of different commutators on one side of the machine, relatively to one another as shown in Fig. 8. By this means 115 the field set up by an armature conductor is 120 125

caused to diminish while the field set up by the overlying or underlying armature conductor is increasing, and vice versa.

Instead of staggering the brushes relatively to one another, the segments may be staggered, a portion of the armature conductors being bent off laterally.

In Fig. 11, the iron body of Fig. 6 is shown laminated.

10 Having now described my invention what I claim as new and desire to secure by Letters Patent is:—

1. A uni-polar dynamo electric machine including two commutators separated by a magnetic field, a plurality of armature conductors terminating in the segments of the aforesaid commutators, a brush rocker comprising a plurality of segments rotatable about said conductors and serving as return conductors whereby the armature conductors are connected in series.

2. A uni-polar dynamo electric machine including two commutators separated by a magnetic field, a plurality of armature conductors terminating in the segments of the aforesaid commutators, a brush rocker comprising a plurality of segments rotatable about said conductors and serving as return conductors whereby the armature conductors are connected in series and wherein those brushes which are connected together by one and the same conductor segment, are shifted relatively to each other one division or brush pitch distance.

3. A uni-polar dynamo electric machine including two commutators separated by a magnetic field, a plurality of armature conductors terminating in the segments of the aforesaid commutators, a brush rocker comprising a plurality of segments rotatable about said conductors and serving as return conductors, together with slip rings rotating with the brush rocker to which rings the ends of the windings are connected, whereby current may be led to and taken from the armature conductors.

4. A uni-polar dynamo electric machine including armature conductors and renewable commutator segments, together with a ring disposed around the commutator for shrinking the segments on to the conductors and recesses in the segments under the ring for preventing the flow of strong magnetic flux through the segments.

5. A uni-polar dynamo electric machine including two commutators separated by a magnetic field, a plurality of armature conductors terminating in the segments of the aforesaid commutators, a brush rocker comprising a plurality of segments and brushes rotatable about the armature segments, these several segments of the brush rocker serving as return conductors whereby the armature conductors are connected in series, the segments and brushes rotatable about the armature segments, these several segments of the brush rocker serving as return conductors whereby the armature conductors are connected in series, the segments and brushes rotatable about the armature segments, these several segments of the brush rocker serving as return conductors whereby the armature conductors are connected in series.

prising a plurality of segments and brushes 60 rotatable about the armature segments, these several segments of the brush rocker serving as return conductors whereby the armature conductors are connected in series, the rotatable brush rocker consisting of a hollow 65 iron cylinder through which the return conductors, which serve also as brush holders, are led but insulated therefrom.

6. A uni-polar dynamo electric machine including two commutators separated by a 70 magnetic field, a plurality of armature conductors terminating in the segments of the aforesaid commutators, a brush rocker comprising a plurality of segments and brushes 75 rotatable about the armature segments, these several segments of the brush rockers serving as return conductors whereby the armature conductors are connected in series, the rotatable brush rocker consisting of a hollow iron cylinder comprising a plurality of 80 laminations through which the return conductors, which serve also as brush holders, are led but insulated therefrom.

7. A uni-polar dynamo electric machine including two commutators on each side of 85 a magnetic field, separated axially, a plurality of armature conductors arranged in at least two layers terminating in the segments of the aforesaid commutators, a brush rocker comprising a plurality of segments and brushes 90 rotatable about the armature segments, these several segments of the brush rocker serving as return conductors whereby the armature conductors are connected in series.

8. A uni-polar dynamo electric machine including two commutators on each side of a magnetic field, separated axially, a plurality of armature conductors arranged in at least two layers terminating in the segments of the aforesaid commutators, a brush rocker comprising a plurality of segments and brushes 100 rotatable about the armature segments, these several segments of the brush rocker serving as return conductors 105 whereby the armature conductors are connected in series, the brushes of different commutators on one side of the machine being staggered relatively to one another for the purpose of suppressing the E. M. F. due 110 to self-induction which occurs on the disconnection of each armature conductor.

In testimony whereof, I have affixed my signature.

RUDOLF KNOLL.
